Attorney

UNITED STATES PATENT OFFICE.

ALFRED KLOTZ, OF MUNICH, GERMANY.

PNEUMATIC INSERTION FOR BOOTS.

Application filed May 3, 1924. Serial No. 710,779.

To all whom it may concern:

Be it known that I, ALFRED KLOTZ, a citizen of the German Republic, residing at Munich, Germany, have invented certain new and useful Improvements in Pneumatic Insertions for Boots, of which the following is a specification.

The commonly used pneumatic insertions for boots consist of an oblong air cushion 10 which serves essentially for supporting the longitudinal arch of the foot.

This invention relates to a pneumatic insertion for boots which is not only designed to raise the longitudinal arch but further, 15 owing to its peculiar shape, to support at the same time the transverse arch of the foot close to the thenar eminence.

In this manner the sore or tender places 20 near the thenar eminence are relieved so that all the painful phenomenæ disappear in most cases almost instantaneously.

According to this invention the air cushion has at the front end an extension which terminates just behind the thenar eminence 25 of the median toes and leaves at either side a free space for the pillar-like acting eminences of the big and little toes.

An embodiment of the invention is shown 30 by way of example on the accompanying drawing, the only figure of which shows in plan view an air cushion constructed in accordance with the invention.

The usual part *a* of the air cushion which supports mainly the longitudinal arch of the 35 foot is fixed on the flexible sole *b* of leather or other convenient material.

The air cushion *a* has an extension *c* directed towards the joint of the toes and vaulted like a kidney, said extension terminating a short distance behind the rear toe 40 joints of the second, third and fourth toes.

The advancing extension *c* leaves at the two sides *d*, *e*, a sufficiently large space for the big toe and for the little toe so that the two pillars of the front transverse arch for the toe joint,—viz. the big toe and the little toe-eminences—rest upon the sole *b* which forms the support, the middle part of the transverse arch being well supported by the advanced part of the air cushion. In this manner the longitudinal or instep arch and the central part of the transversal or metatarsal arch of the foot are separately and adjustably supported and corrected.

It may be mentioned that the characteristic feature of the invention consists in the arrangement of an extension *c*, the air cushion itself being of any desired construction. The inner space of the air cushion may be subdivided into two or more non-communicating compartments, for instance into two, as illustrated, or it may be composed of two separate parts, a main part and a front secondary part, said parts joining one another directly or being arranged at a convenient distance apart. Each individual compartment has its own air valve.

I claim:—

In combination with a flexible insole for boots or shoes, an inflatable air cushion adapted to support the instep arch of the foot and having an extension at its front part, the latter presenting a non-communicating separately-inflatable air cushion, localized at the center of the metatarsal arch.

In testimony whereof I affix my signature in presence of two witnesses.

ALFRED KLOTZ.
